UNITED STATES PATENT OFFICE.

FRANK A. HINDS, OF WATERTOWN, NEW YORK.

ROTARY WATER-METER.

SPECIFICATION forming part of Letters Patent No. 314,126, dated March 17, 1885.

Application filed November 22, 1884. (No model.)

To all whom it may concern:

Be it known that I, FRANK A. HINDS, of Watertown, in the county of Jefferson and State of New York, have invented certain new and useful Improvements in Water-Meters; and I do hereby declare that the following is a full, clear, and exact description of the invention, which will enable others skilled in the art to which it appertains to make and use the same, reference being had to the accompanying drawings, which form a part of this specification, and in which—

Figure 1 is a horizontal sectional view of my improved water-meter. Fig. 2 is a vertical sectional view of the same taken on the line 1 2 in Fig. 1. Fig. 3 is a horizontal sectional view of a portion of the meter, illustrating a slight modification in the construction thereof, and Fig. 4 is a vertical sectional view taken on the line 5 6 in Fig. 3.

The same letters refer to the same parts in all the figures.

This invention relates to water-meters of that class which are provided with a rotary piston; and it has for its object to so construct the same as to compensate for wear upon its component parts during the operation of the meter, thus causing the latter to measure accurately and without loss from leakage.

The invention further has for its object to provide a device which shall possess superior advantages in point of simplicity, durability, and general efficiency.

With these ends in view the invention consists in the improved construction and arrangement of parts, which will be hereinafter fully described, and particularly pointed out in the claims.

In the drawings hereto annexed, A designates the outer case, which is bolted to the bottom piece, C, which latter is provided with a cylinder, B, extending upwardly into the outer casing eccentrically with the latter.

Secured centrally to the bottom piece, C, is a vertical spindle, D, upon which revolves an inverted-cup shaped cylinder, B², the lower edge of which bears upon or against the bottom piece, C, while the cylindrical collar B of the latter bears at its upper edge against the under side of the top of the cylinder B². It will thus be seen that wear upon the edges,

which are designated by b and b², is mutually compensated for, so that the parts B, B², and C shall always be tightly fitted together, and the interior space, which is designated by letter E, be absolutely water-tight. The cylindrical collar B is provided with entrance and exit ports a' and b', connected, respectively, with the entrance and exit pipes a³ and b³, and opening into the space E, near the narrow or small side of the latter, at which the parts B and B² are nearly in contact with each other. The cylindrical collar B is provided at an intermediate point between the ports with a recess, in which is hinged a vibrating valve, c, the free edge of the wing of which bears against the inner side of the cylinder B², with which it is constantly held in contact, partly by the back-pressure of the water in the space E, and partly by the action of a suitably-arranged spring, c². The inner side of the cylinder B² is provided with diametrically-opposite recesses, in which are pivoted vibrating valves e, extending between the bottom piece, C, and the top of the cylinder B², and the ends of the wings of which bear against the wall of the inner cylindrical collar, B. The said valves are retained automatically in an open position partly by the pressure of the water passing through the meter and partly by the action of suitably-arranged springs i i, arranged in recesses in the wall of the cylinder B², and bearing or pressing against the inner sides of the wings of the said valves.

It is obvious that the wings of the valves c and e are to face in opposite directions, in order to enable the latter to pass freely over the former as the cylinder B² revolves. The top of the cap or casing A is provided with a central bearing, o, provided with a packing-box, p, for a small spindle, s, the lower end of which is provided with a firmly-seured arm or lever, g, connecting it with a pin, d, extending upwardly from the revolving cylinder B². The spindle s, which is thus caused to revolve with the latter, is connected by a suitable gear to a decimal train and index, (not shown in the drawings,) which, by registering the number of revolutions of the cylinder B², will denote the exact quantity of water passed through, since one revolution of the said cylinder B² will cause to be dis-

charged the amount of water that can be contained in the space E, the capacity of which must of course be known.

The operation and advantages of this invention will be readily understood from the foregoing description, taken in connection with the drawings hereto annexed. The wear upon the upper and lower edges of the cylinders B and B² will be substantially equal, and will be compensated for by the weight of the cylinder B², which practically rests upon the bottom plate, C. In like manner the wear upon the upper and lower edges of the several valves is compensated for. The inner or free edges of the several valves are constantly held by their respective springs, as well as by the water-pressure, against their bearings, and as they become worn will simply open a little farther. The operation of the device will thus continue uninterruptedly and accurately until the device is worn out, or until the valves have been worn down so far as to be inoperative. The entrance-pipe a³ of the meter is to be provided with a small opening, n, communicating with the space N between the cylinder B² and the outer casing, filling the said space with water, the pressure of which will serve to force the cylinder B² against its bearings. This pressure may be augmented by means of a small opening, m, connecting the exit-port b' with the interior of the cylindrical collar B, since the pressure in the exit-port is less than that in the inlet-port by the amount of pressure required to move or operate the meter. In case of any considerable wear upon the edges b and b' of the parts B and B², this may be compensated for by tightening the nut N', which serves to secure the cylinder B² upon the spindle D, and in case of wear upon the latter by the revolution of the cylinder B² the joint is still kept tight by means of a washer, W, arranged under the said nut N', and kept from revolving upon the spindle by any suitable means.

The modification of my invention shown in Figs. 3 and 4 of the drawings consists simply in substituting for the valve e (shown in Figs. 1 and 2) a cylindrical rolling valve, y, forced against its bearings by the back-pressure of the water, assisted by a suitable spring, x.

The operation is precisely as above described; but this construction may be found to be more durable and satisfactory than the construction illustrated in the preceding figures.

Other changes in the construction of this device may by extended trial be found useful, and I would therefore have it understood that I do not limit myself to the precise con-

struction herein shown, but reserve to myself 60 the right to all such modifications as may be resorted to without departing from the spirit of my invention.

Having thus described my invention, I claim and desire to secure by Letters Patent of the 65 United States—

1. In a water-meter, the combination, with a suitable casing having an interior eccentric cylindrical collar, of a central or concentric inverted-cup-shaped cylinder fitted over and 70 revolving around the said collar, suitable valves or gates attached to the revolving cylinder, a cut-off attached to the cylindrical collar, and entrance and exit ports on either side of the said cut-off, substantially as and for the 75 purpose herein set forth.

2. In a water-meter, the combination, with a casing having an interior eccentric cylindrical collar, and an inverted-cup-shaped cylinder arranged to revolve over and around the 80 same, of the water inlet and outlet, suitable gates or valves, a cut-off, and openings admitting water to the spaces between the outer casing and the revolving cylinder and between the interior of the latter and the space 85 inside the eccentric collar, substantially as and for the purpose herein set forth.

3. In a water-meter, the combination, with a casing having an interior eccentric cylindrical collar, of a central revolving inverted- 90 cup-shaped cylinder, and vibrating valves or gates hinged to the inner side of the latter, and adapted to bear against the outer side of the eccentric collar, substantially as and for the purpose set forth.

4. The combination of the base-plate having a central spindle and an eccentric cylindrical collar with the outer casing or covering, and an inverted-cup-shaped revolving cylinder mounted upon the said spindle, vibrating gates 100 hinged to the inner side of the revolving cylinder, a cut-off valve attached to the eccentric collar between suitable inlet and exit ports, and openings arranged to admit water under pressure to the spaces between the outer 105 casing and the revolving cylinder and to the interior of the eccentric collar against the under side of the top of the said revolving cylinder, substantially as and for the purpose herein set forth.

In testimony that I claim the foregoing as my own I have hereunto affixed my signature in presence of two witnesses.

FRANK A. HINDS.
